UNITED STATES PATENT OFFICE.

LOUIS JOHN McCRRORY AND RALPH EARL BAKER, OF CHICAGO, ILLINOIS.

SANITARY TOOTHPICK HOLDER.

Application filed July 9, 1926. Serial No. 121,314.

Our invention consists of a sanitary toothpick holder and has for its object the provision of a means for delivering toothpicks in a safe, sanitary and economical 5 manner.

Another object of our invention is the provision, in a device of the character described, of a means whereby the operation of removing a toothpick from the holder 10 will automatically provide another toothpick ready for removal.

Another object of our invention is the provision, in a device of the character described, of a means for providing for removal therefrom only one toothpick at a 15 time, thereby preventing waste of said toothpicks.

Another object of our invention is the provision in a device of the character described of a means of providing toothpicks for removal therefrom without the interposition of human hands, thereby effecting 20 said delivery in a sanitary manner.

Another object of our invention is to provide, in a device of the character described, means whereby said toothpicks will be prevented from jamming in said holder, thereby promoting the delivery of said toothpicks in a uniform manner.

With the above and other objects in view, the invention consists of the combination and arrangement of parts hereinafter described and claimed, it being understood that within the scope of what is claimed, 35 changes in the precise embodiment of the invention shown can be made, without departing from the spirit of our invention.

In the drawings—

Figure 1 is a sectional view of our invention transversely through the delivery chute and reservoir thereof;

Figure 2 is a sectional view along the line 2—2 of Figure 1;

Figure 3 is a detail of the feeder arm.

Referring more particularly to the drawings, toothpicks are placed in the receptacle B and are delivered through the chute A. When a toothpick such as M is removed from the said chute A, said chute oscillates 50 on the trunnions 1, rotatably mounted in the container H, communicating its motion to the link C by means of the pin 9, the other end of the link being rotatably attached to the crank G by means of the pin 8, said crank G being mounted on the shaft 7 journaled in the bracket 10 supported by

the container H. The relative location of the pins 8 and 9 and link C is such that about ten degrees rotation of the chute A will cause about ninety degrees rotation of the crank G about its shaft 7. The pins 4 and 5 are affixed at opposite points on the crank G, engaging respectively in the slot 3 provided in the finger E and the slot 6 provided in the finger D so as to permit vertical movement of the fingers D and E 65 slidably positioned in the bracket 10 supported by the container H. Attached to the finger E by means of the arm 2 is the feeder F having provided on its upper side a plurality of serrations 13 and on the discharge side the cam face 12, said feeder F being positioned in the slots 17 provided in the floor 15 of the reservoir B so as to thereby form the feeder lips 11. As the crank G rotates 70 as heretofore described, the finger D rises and the finger E lowers so as to permit a toothpick such as J to pass into the position as shown at L and resting against the finger D, the said movement of the said toothpick 75 being aided by the cam face 12. Further downward movement of the finger E causes the feeder F attached to said finger, to pass below the said feeder lips 11 so as to leave a row of toothpicks similar to those shown 80 as at K resting on said feeder lip, the action of gravity causing one of the said toothpicks K to pass through the opening 16 provided in the front wall of the said reservoir B so as to take approximately the 85 position as at J, said opening 16 being formed with the notches 18 so as to permit the feeder F to project upwardly therein. When the toothpick M is entirely removed 90 from the chute A, said chute is caused by gravity to oscillate about the trunnion 1 in the reverse manner to that heretofore described, so as to thereby cause the finger D to lower and release the toothpick L into the chute A, said toothpick being aided in 95 its movement by the rising finger E, said finger at the same time forcing the toothpick J into its position as shown. At the same time the feeder F rises into the reservoir B, agitating the toothpicks therein and arranging the bottom row thereof in order 100 as shown at K.

The chute A is shaped so as to permit one end of a toothpick such as L, as said toothpick is delivered therein, to have a freer fall 110 than the other end; at the same time the said chute is sloped downwardly and to one side.

so as to cause said free end to advance ahead of the other end of said toothpick, thereby causing said toothpick to assume the position as shown at M, said toothpick being restrained from complete emergence from said chute by means of the spring 14 positioned in the said chute at the delivery end thereof.

In the preferred embodiment of our invention, as shown, we have indicated two feeder mechanisms comprising the cranks G, fingers D and E, feeders F, brackets 10 and associated parts as substantially indicated in Figure 2, the motion of the first said crank G rotatably attached to the link C being communicated to the other crank G by the shaft 7, but it is obvious that more or less such mechanisms may be used at the option of the person constructing the device.

We claim:

1. In a sanitary toothpick holder, the combination of a container, a toothpick reservoir positioned in said container, a delivery chute oscillatably mounted on trunnions positioned in said container, said chute being sloped downwardly and to one side and having provided at its delivery end a spring whereby to prevent the complete emergence of toothpicks therefrom, delivery lips provided on the lower portion of said reservoir and registering with said delivery chute, mutually reciprocating fingers positioned intermediate said delivery lips, feeders cooperating with said fingers and positioned rearwardly thereof, so as to be capable of projecting upwardly into said reservoir, said feeders having provided on their upper side a plurality of serrations and having provided on the side towards the said fingers a cam shaped face, and means for communicating the oscillatory motion of said chute to said reciprocating fingers and said feeders.

2. In a sanitary toothpick holder, the combination of a container, a delivery chute oscillatably mounted on trunnions positioned in said container, said chute being sloped downwardly and to one side and having provided at its delivery end a spring whereby to prevent the complete emergence of toothpicks therefrom, a link pivotally mounted on the back of said chute, a bracket supported by the said container, a crank rotatably mounted on said bracket, said link being piv-

otally mounted on said crank, so that an oscillatory motion of about ten degrees of said chute will cause a rotation of said crank of about ninety degrees, pins positioned oppositely on said crank, mutually reciprocating fingers positioned vertically in said bracket one in front of the other and having provided at their lower end slots suitably to engage said pins, whereby the said rotation of said crank may be converted into the vertically reciprocating motion of said fingers so that as one finger goes up the other comes down, and means for delivering toothpicks to said fingers, substantially as described, so that the mutually reciprocating action of said fingers will cause said toothpicks to be delivered to said chute.

3. In a device of the character described, a container, a delivery chute oscillatably mounted on trunnions positioned in said container, a toothpick reservoir positioned in said container suitably to register with said chute, delivery lips provided on the bottom of said reservoir, said lips being provided with slots extending rearwardly therefrom and into the floor of the said reservoir, mutually reciprocating fingers positioned one rearwardly the other in said slots, a feeder positioned behind the said rearward finger and affixed thereto but having its top surface above the top of said rearward finger, and also having provided its top surface at a slope corresponding to the slope of the floor of said reservoir, said top surface having provided therein a plurality of serrations of a size corresponding to a toothpick, said feeder furthermore having provided on the side facing said rearward finger an upwardly and outwardly sloping surface or cam, the lower edge of said surface corresponding to the top of said rearward finger, an opening provided in the front wall of said reservoir above said delivery lips so as to permit the passage of toothpicks therethrough, and means for causing the reciprocating action of said fingers and said feeders, substantially as described.

In testimony whereof we affix our signatures.

LOUIS JOHN MCCRARY.
RALPH EARL BAKER.
